UNITED STATES PATENT OFFICE.

LYMAN M. WAITE, OF FITCHBURG, MASSACHUSETTS, ASSIGNOR TO FITCHBURG MACHINE WORKS, OF FITCHBURG, MASSACHUSETTS, A CORPORATION OF MASSACHUSETTS.

MULTIPLE-SPINDLE LATHE.

1,125,779.

Specification of Letters Patent.

Patented Jan. 19, 1915.

Application filed January 5, 1914. Serial No. 810,305.

To all whom it may concern:

Be it known that I, LYMAN M. WAITE, a citizen of the United States, residing at Fitchburg, in the county of Worcester and 5 State of Massachusetts, have invented a new and useful Multiple-Spindle Lathe, of which the following is a specification.

This invention relates to a multiple spindle lathe and particularly to that type of 10 lathe which is shown in Letters-Patent No. 926,736, granted July 6, 1909 to J. J. Grant. In this type of lathe the tools are held in a fixed tool head and the work holding spindles are mounted in a supporting head 15 which is longitudinally movable relative to the fixed tool head. Each spindle is rotatable upon its own axis and the supporting head as a whole is intermittently turned through a partial revolution to advance the 20 work successively into relation with the different tools. Mechanism is also provided for locking the head in each of its operative positions.

It is the object of my invention to improve 25 the mechanism for intermittently rotating and locking the supporting head above described while at the same time providing for economy of manufacture and for simplicity and reliability in the operating parts.

30 With this object in view my invention comprises certain devices, arrangements and combinations of parts which will be herein-after described and more particularly pointed out in the appended claims.

35 A preferred form of my invention is shown in the drawings in which—

Figure 1 is a side elevation of a portion of 40 a multiple spindle lathe with my improved feeding and locking devices applied thereto; Fig. 2 is an end elevation partly in section; and Fig. 3 is a detail view of the locking device.

The lathe to which I have applied my improvements consists essentially of a frame 45 10 having integral therewith at one end a fixed tool head 11 and provided with ways 12 upon which the supporting head 13 is longitudinally movable. The supporting head comprises a casing 14 within which is 50 rotatably mounted a spindle carrier 15 having secured therein a plurality of hollow spindles 16. At one end these spindles are provided with work holding chucks 17 and

upon their opposite ends they may be furnished with any suitable chuck operating 55 means 18. Each of these spindles 16 is rotatable upon its own axis, the driving means for producing this rotation constituting no part of my invention and being omitted to avoid confusion on the drawings. The spindle carrier 15 is provided at its rear end with a gear 19 meshing with a pinion 20. The pinion 20 is secured to a counter-shaft 21 rotatable in a bearing 22 upon the supporting head 14 and in a bearing 23 fixed to the 60 frame of the lathe. The shaft 21 is extended to the right beyond the bearing 23 for purposes not pertaining to this invention. A second pinion 24 is secured to the counter-shaft 21, the said counter-shaft being held in the bearing 22 by a collar 21^a and a washer 21^b, so that the shaft and pinions move longitudinally of the lathe with the head 13. A segment gear 25 is rotatably mounted in a bracket 26 secured to the frame 65 10 and is so positioned that it will mesh with the pinion 24 when the head 13 occupies its rearmost or retracted position. A link 27 is pivotally connected at its upper end to the segment gear 25 and at its lower end to 70 one arm of the three-armed lever 28. The two other arms of the lever 28 are provided upon opposite sides with cam rolls 29 which coöperate with a pair of edge cams 30, fixed upon a cam shaft 31. The cams 30 are so 75 timed with relation to the movement of the supporting head 13 that the segment 25 will occupy the position shown in Fig. 2 when the pinion 24 reaches its retracted position. The lever 28 is thereafter moved by the cams 80 30 to swing the segment 25 upward, giving it a sufficient angular movement to cause the spindle carrier 15 to make one quarter of a revolution. The extent of this movement may be varied by the selection of suitable cams and should correspond to the 85 number of spindles mounted in the spindle carrier. It is sometimes found desirable to give the spindles twice the usual angular advance at each stop, stopping each spindle 90 in line with alternate tools. This method of operation may also be accomplished by the use of cams of suitable dimensions. The cams 30 thereafter retain the segment 25 in its raised position until the supporting head 95 100 is again moved forward and the pinion 24 is again moved forward and the pinion 24

is out of mesh with the segment, when the segment is returned to its lower position by the cams 30.

In order that the spindle carrier may be held from rotation during the period when the pinion 24 and the segment 25 are out of mesh a locking device is provided which is shown most clearly in Fig. 3. The carrier 15 is provided with a plurality of bushings 32 which provide tapered recesses in the carrier. A tapered stud 32^a is formed in the center of each bushing, the taper of the stud being at a less angle than the taper of the bushing. A tapered plunger 33 mounted in a boss 34 projecting from the lower side of the casing 14 cooperates with the recesses in the bushings 32 to lock the carrier against rotation. The plunger 33 has centrally located in its upper end a recess corresponding in taper to the stud 32^a and closely fitting said stud when the plunger is in locking position. The plunger 33 has adjustably secured thereto a double flanged collar 35 adapted to receive a pin 36 between its flanges. The pin 36 is mounted in a locking lever 37 pivotally secured at 38 to a bracket 39 depending from the casing 14. The lever 37 is provided upon each side with a cam roll 40 each adapted to cooperate with one of a pair of edge cams 41 mounted to rotate with the cam shaft 31, and rigidly secured thereto. The cams cooperate with the rolls 40 to move the lever 37 when the head 13 is substantially in retracted position. A spring 42 tends constantly to move the plunger 33 to its locking position. The timing of the cams 41 is such that the plunger is withdrawn as the head 13 reaches its retracted position and is advanced as soon as the segment 25 has turned the carrier 15 through its partial rotation. As the lever 37 is positively moved by the cams 41, the tapered plunger 33 is forced into the bushing 32 and will overcome any slight inaccuracies in the spacing of the carrier. As the plunger nears its final locking position, the slightly tapered recess coacts with the stud 32^a, assisting the accurate indexing of the head. Reference to the drawings will show that the length of the stud 32^a is substantially equal to one-half of the depth of the recess in the bushing 32. As the carrier 15 approaches its final position the outer portion of the stud 33 will often strike against the side of the recess in the bushing 32 near its outer end and it is at these points that the greatest wear occurs. By the time that the plunger has been moved into the bushing as far as the end of the stud 32^a the rotative movement of the carrier 15 will be substantially checked. As the plunger approaches its seat the worn end of the plunger coacts with the accurate portion of the bushing, while the worn part of the bushing coacts with the accurate part of the plunger.

Thus the accurate or unworn parts of these two elements never come into operative relation to each other and it is under these circumstances that the final indexing action of the recess and stud becomes increasingly important and by their operation the period of accurate indexing by the machine is very materially prolonged. The lever 37 is extended to the right (Fig. 2) to form a handle 43 by which the plunger 33 may be manually withdrawn should occasion arise. It is essential in the operation of this feeding and locking mechanism that all backlash should be as far as possible eliminated, particularly when the feeding mechanism approaches its final position and in order that the pinion 24 and the segment 25 may be closely in mesh under these conditions, I have provided the segment 25 with adjustable teeth 44. These teeth are formed upon a sliding block 45 which is adjusted radially by a set screw 46 and may be clamped in adjusted position by a screw 47. The usual cross feed 48 is mounted upon the front end of the supporting head 13 but forms no part of my invention.

Having thus described my invention, it will be evident that many changes and modifications can be made therein by those skilled in the art without departing from the spirit and scope thereof as set forth in the claims and I do not wish to be limited to the details herein disclosed, but

What I do claim is:—

1. A multiple spindle lathe having in combination, a longitudinally movable work supporting head, mechanism for intermittently rotating said head including a pinion and a segment gear, means for intermittently locking said head against rotation, a rotating cam shaft and a plurality of cams on said shaft effective to operate said means and said mechanism respectively, the cam for operating said mechanism having a dwell which permits the segment gear to remain stationary while the pinion is moved into mesh therewith.

2. A multiple spindle lathe having in combination, a longitudinally movable head, a plurality of work holding devices rotatable in said head, means to lock the head in any one of a plurality of operative positions, mechanism to intermittently rotate the head including a pinion and a segment gear meshing therewith when the head is in its rear position only, a continuously rotating cam shaft, and cams on said shaft for releasing said locking means and actuating said mechanism, the cam for actuating said mechanism being effective to hold the segment gear in fixed position while the pinion is moved into mesh therewith.

3. A multiple spindle lathe having in combination, a longitudinally movable head, a plurality of work holding devices rotata-

ble in said head and mechanism for intermittently rotating said head, said mechanism including a segment gear and means for positively actuating said segment gear in two directions.

4. A multiple spindle lathe having in combination, a longitudinally movable head, a plurality of work holding devices rotatable in said head and mechanism for intermittently rotating said head comprising a gear on the head, a counter-shaft mounted on the head and longitudinally movable with the head, a pinion on the counter-shaft meshing with said gear, a second pinion on the counter-shaft, a segment gear mounted on the lathe frame with which said second pinion meshes when the head is in retracted position only, and cam-operated means for intermittently moving said segment gear.

5. A multiple spindle lathe having in combination, a longitudinally movable work supporting head and means for intermittently rotating said head comprising a pinion on the head, a segment gear, a link connected at one end to said gear, a three-armed lever having one arm connected to the lower end of the link and having cam rolls upon the remaining two arms, a rotating cam shaft, and a pair of cams on said shaft cooperating with said rolls to intermittently rotate the head.

6. A multiple spindle lathe having in combination, a longitudinally movable work supporting head and means for intermittently, partially rotating said head, said

means comprising a segment gear having certain of its teeth radially adjustable to compensate for back lash in the teeth or bearings.

7. A multiple spindle lathe having in combination an intermittently rotatable head, a plurality of work holding devices rotatable in said head, and means to lock the head in any one of a plurality of operative positions, said means comprising a series of tapered bushings in said head, each bushing having a tapered stud therein, and a tapered locking plunger fitting said bushing and having a recess therein fitting said stud.

8. A multiple spindle lathe having in combination an intermittently rotatable head, a plurality of work holding devices rotatable in said head, and means to lock the head in any one of a plurality of operative positions, said means comprising a series of tapered bushings in said head, each bushing having a tapered stud therein, and a tapered locking plunger fitting said bushing and having a recess therein fitting said stud, the taper of the stud and recess being formed at a less angle than the taper of the plunger and bushing.

In testimony whereof I have hereunto set my hand, in the presence of two subscribing witnesses.

LYMAN M. WAITE.
